UNITED STATES PATENT OFFICE.

EDGAR H. COTTRELL, OF STONINGTON, CONNECTICUT, ASSIGNOR TO C. B. COTTRELL & SONS COMPANY, OF NEW YORK, N. Y., A CORPORATION OF NEW JERSEY.

CUTTING AND FOLDING MACHINE.

1,067,470.

Specification of Letters Patent. Patented July 15, 1913.

Application filed July 12, 1907. Serial No. 383,402.

To all whom it may concern:

Be it known that I, Edgar H. Cottrell, a citizen of the United States, and resident of Stonington, in the county of New London 5 and State of Connecticut, have invented a new and useful Improvement in Cutting and Folding Machines, of which the following is a specification.

This invention relates to an improvement 10 in cutting and folding machines and has for its object to provide means for so associating extra sheets fed from a separate source of supply with sheets cut and fed from the main press that the said extra 15 sheets may occupy different positions in the completed signature.

This invention is more particularly directed to means for so associating sheets fed from the main press web with insert sheets 20 and a cover sheet that the position of the insert sheets in the completed signature may be varied to suit different requirements, the sources of insert sheet supply being made independently adjustable so that the insert 25 sheets may be fed to different positions in the width of the main press sheets before the same are slit and deposited in the delivery carrier.

In the accompanying drawings, Figure 1 30 is a vertical longitudinal section through a portion of the cutting and folding machine embodying my invention. Fig. 2 is a view in side elevation showing the geared connections for driving the several parts at 35 their proper speeds with relation to one another. Fig. 3 is a view in elevation of the insert supply end of the machine. Fig. 4 is a view in elevation of the cover supply end of the machine. Fig. 5 is an enlarged 40 detail section showing the arrangement of the cams for actuating the folding mechanism of the folding cylinders. Fig. 6 is an enlarged detail section taken inside the side framing showing the arrangement of cams 45 for controlling the operation of the grippers on certain of the cylinders. Fig. 6^a is a detail plan of one of the cams for controlling the operation of the opening cam for the grippers on the sheet collecting cylinder. 50 Fig. 7 is a detail end view of the machine showing a source of insert supply on the same end of the machine as the source of cover sheet supply and so arranged that it will be associated with the third group of

collected sheets from the main press web 55 in the completed signature. Fig. 8 is a detail end view of the machine showing two sources of insert supply on one end of the machine, instead of one source of insert supply as shown in Fig. 3 and so arranged 60 that they will be associated with the second and fourth groups of collected sheets from the main press web in the completed signature. Figs. 9, 10, 11, 12 and 13 represent several different combinations of main web, 65 insert and cover sheets which may be obtained in the completed signature by shifting the insert supply, and varying the number of sources of insert supply; Fig. 9 representing the combination produced in the 70 form shown in Figs. 1 to 6 inclusive and Fig. 11 showing the combination produced in the form shown in Figs. 7 and 8. Fig. 14 is a detail section on an enlarged scale 75 showing the cam for controlling the movement of the floating folding blade on the male folding cylinder.

The side frames of the machine are denoted by 1 and 2. Male and female folding cylinders 3, 4, are mounted between the 80 side frames, the male cylinder being provided with a set of grippers 5 and a floating folding blade 6 and the female folding cylinder being provided with a set of grippers 7 and floating folding jaws 8, which jaws 85 are arranged to coact with the blade 6 of the male folding cylinder.

A collecting cylinder 9 is arranged adjacent to the male folding cylinder 3 and it is provided with a set of grippers 10. An insert transfer cylinder 11 is located adjacent to the male folding cylinder 3, which transfer cylinder is provided with a set of grippers 12. A cover sheet transfer cylinder 13 is located adjacent to the female folding 95 cylinder 4 and it is provided with a set of grippers 14. The printed web 15 is fed from the main press, not shown herein, past the feeding tapes 16 through rotary cutters 17, 18, and from thence between stationary guides 19, 20, into position to have the advance edges of the sheet engaged by the set of grippers 10 on the collecting cylinder 9. A previously printed insert web 21 leads from the roll 22 past feeding tapes 23 through rotary cutters 24, 25, and from thence between stationary guides 26, 27, into position to have the advance edges of

the sheets engaged by the set of grippers 12 on the transfer cylinder 11. The previously printed insert web 21 may be wound with an offset web 28 for preventing the smutting of the insert web, the offset web being wound off the web 22 on to the roll 29 as the insert web is unwound from the roll 22. The insert web roll 22 is mounted on its shaft in any desired position laterally of the machine so that the sheets which are cut from the insert web 21 will be fed to any desired point in the width of the collected sheets cut and fed from the main press web 15.

15 A previously printed cover web 30 leads from a roll 31 past feeding tapes 32 through rotary cutters 33, 34, and from thence between stationary guides 35, 36, into position to have the advance edges of the sheets engaged by the set of grippers 14 of the transfer cylinder 13. The previously printed cover web 30 may be wound with an offset web 37 for preventing the smutting of the cover web, the offset web being wound off the roll 31 on to the roll 38 as the cover web is unwound from the roll 31. The cover web roll 31 is mounted on its shaft in any desired position laterally of the machine so as to permit the sheets which are cut therefrom to be fed to any desired point in the width of the collected sheets cut and fed from the main press web 15.

20 The several mechanisms are driven from the press through the train of gears 39, 40, 41, the gear 41 meshing with a gear 42 fixed to the shaft 43 of the male folding cylinder 3. The female folding cylinder 4 is driven at the same speed as the cylinder 3, by means of a gear 44 on the shaft 43 which meshes 25 with a gear 45 on the shaft 46 of the female folding cylinder 4. The collecting cylinder 9 is driven two revolutions to one of the male folding cylinder 3, by a gear 47 fixed to the shaft 48 of the cylinder 9, which 30 gear meshes with the gear 42 of the cylinder 3. The feed roller shaft 49 for the cylinder 9 is driven from the said cylinder by a gear 50 which meshes with the gear 47. The 35 previously printed insert sheet transfer cylinder 11 is driven a revolution for every revolution of the male folding cylinder 3 but at varying speeds, by irregular gears, one gear 51 being fixed to the shaft 43 of the cylinder 3 and the other gear 52 being fixed to the shaft 53 of the said transfer cylinder 40. The feed roller shaft 54 for the cylinder 11 is provided with a gear 55 which meshes with a gear 56 fixed on the shaft 53 of the cylinder 11. The previously printed cover sheet transfer cylinder 13 is driven a revolution for every revolution of the female folding cylinder 4 but at varying speeds, by irregular gears, the gear 57 being fixed to the shaft 46 of the female folding cylinder 45 and the gear 58 being fixed to the shaft 59

of the transfer cylinder 13. The feed roller shaft 60 for the cylinder 13 is provided with a gear 61 which meshes with a gear 62 fixed to the shaft 59 of the transfer cylinder 13.

Sheet pressure rollers 63, 64, 65, 66 engage 70 the peripheries of the cylinders 4, 9, 3 and 11 respectively, for holding the sheets against the peripheries of these cylinders when the sheets are disengaged from their grippers. Carrying tapes 67, 68 are arranged to convey the assembled and folded group of press, insert and cover sheets from the female folding cylinder 4 through slitters 69, 70, to a predetermined point, such, for instance as a collecting pocket carrier 71 80 like that shown in my United States Letters Patent No. 749,362 dated January 12, 1904.

85 The insert offset roll 29 is driven from the gear 45 of the cylinder 4, through the train of gears 72, 73, 73*, 74, 75, 76, 76*, shaft 77 and train of gears 77*, 78, 79, 80, 81. The cover offset roll 38 is driven from the gear 72 through a train of gears 73, 73**, 84, 85, 86, 87, 88. The rotary cutters 17, 18, are 90 driven from the gear 45 through a train of gears 89, 90, 91, 92, 93, and the rotary cutters 24, 25 are driven from the gear 91 through a train of gears 94, 95, 96, 97, 98. The rotary cutters 33, 34, are driven from 95 the gear 90 through a train of gears 99, 100, 101. The web feeding tapes 23, 16 and 32 are driven from their respective cutters by suitable gearing which need not be specifically described.

100 The set of grippers 10 on the sheet collecting cylinder 9 is opened every revolution to receive the advance edge of a sheet from the main press by means of a fixed cam 102 which engages the gripper lever 103 at the proper time. The set of grippers 10 is opened every second revolution of the cylinder 9 to transfer a collected group of two sheets from the cylinder 9 to the set of grippers 5 on the male folding cylinder 3, by 105 means of a movable opening cam 104, which cam is thrown into and out of position to engage the lever 103 by means of a rock lever 105 operated by a cam 106 driven from the shaft 53 of the cylinder 11 through gears 110, 107, 108. The set of grippers 12 on the insert sheet transfer cylinder 11 is opened every revolution to receive the advance edge 115 of a sheet from the cutters 24, 25, by a stationary cam 109 which is arranged in position to engage the gripper opening lever 110 at the required time. This set of grippers 12 is opened every revolution of the cylinder 11 to transfer the insert sheet to the set of grippers 5 on the male folding cylinder 3, 120 by means of a fixed cam 111 which engages the lever 110 at the proper point.

125 The set of grippers 14 on the cover sheet transfer cylinder 13 is opened to receive the advance edge of the cover sheet as it leaves 130

- the guides 35, 36, by means of a fixed cam 112 which is arranged in position to engage the gripper opening lever 113 at the proper time. Another fixed cam 114 is arranged in position to engage the lever 113 at the proper time to transfer the advance edge of the cover sheet from the set of grippers 14 to the set of grippers 7 on the female folding cylinder 4. 5
- 10 A fixed cam 115 is arranged in position to engage the opening lever 116 of the set of grippers 7, at the proper time to receive the advance edge of the cover sheet from the set of grippers 14. A second fixed cam 117 is arranged in position to engage the lever 116 of the set of grippers 7 at the proper time to transfer the advance edge of the cover sheet to the set of grippers 5 on the male folding cylinder 3. 15
- 20 A fixed cam 118 is arranged in position to engage the opening lever 119 of the set of grippers 5 on the male folding cylinder 3 at the proper time to receive the advance edge of the insert sheet from the transfer cylinder 11. A second fixed cam 120 is arranged in position to engage the lever 119 at the proper time to open the set of grippers 5 to receive the collected group of two sheets from the main press. A third fixed cam 121 is arranged in position to engage the lever 119 to open the set of grippers 5 to receive the advance edge of the cover sheet from the set of grippers 7. A fourth fixed cam 122 is arranged in position to engage the lever 119 to open the set of grippers 5 to release the advance edges of the assembled group of sheets at the proper time of folding the same from the male folding cylinder on to the female folding cylinder. 30
- 40 The coaction of the folding devices on the cylinders 3 and 4 is obtained as follows: A fixed box cam 123 is arranged to control the floating movement of the blade 6 through the truck roller 124 and a cam 125 is arranged to control the tucking movement of the said blade by its engagement with the stud roll 126. A fixed box cam 127 is arranged to control the floating of the folding jaws by its engagement with the truck roller 128 and a fixed cam 129 is arranged to control the opening of said jaws by its engagement with the stud roll 130. The opening of the floating jaws to release the folded signature at the proper time to permit it to be fed between the tapes 67, 68 is controlled by a stationary cam 131 which engages the stud roller 130*. 45
- 50 The movements of the parts hereinabove described are so timed with respect to each other that the rotary cutters 17, 18, and the sheet collecting cylinder 9 complete two revolutions to one revolution of the folding cylinders. The rotary cutters 24, 25, for the insert web and their transfer cylinder 11, 55 rotate one revolution for one revolution of the folding cylinders so that one insert sheet is transferred to the male folding cylinder for two sheets from the main web delivered from the collecting cylinder 9. The irregular gears 51, 52, are so shaped that the grippers 12 will be caused to travel at the speed of the insert web at the time of engaging the advance edges of the insert sheet and will be caused to travel at the surface speed of the male folding cylinder at the time that the advance edge of the insert sheet is transferred to the grippers 5. The rotary cutters 33, 34, for the cover web and their transfer cylinder 13, complete one revolution for every revolution of the folding cylinders. 70
- 60 The irregular gears 57, 58 are so shaped that the cylinder 13 will be caused to travel at the speed of the cover web at the time the grippers 14 engage the advance edge of the cover sheet and at the surface speed of the female folding cylinder 4 at the time that the advance edge of the cover sheet is transferred to the grippers 7. 75
- 70 In the form shown in Figs. 1 to 6 inclusive, the insert sheets cut and fed from the source of insert supply are associated with the collected sheets cut and fed from the main press web at the same point in the width of the sheets as the sheets cut and fed from the source of cover supply, the cover sheets being fed to one side of the collected group of sheets from the press and the insert sheets being fed to the other side of the collected group. In these figures a single cover sheet and a single insert sheet 80 are shown as combined with the first group of collected sheets from the press in the completed signature and the other three groups of collected sheets from the main press are shown as being successively deposited within the so assembled group of cover, insert and main press sheets. 85
- 80 While I have shown the cover sheets and insert sheets as combined with the first group of collected sheets from the press in the completed signature, it is evident that these cover and insert sheets may be combined in any other manner with any of the four groups of collected sheets from the main press, by shifting the insert and cover sheet web rolls to any desired positions on their shafts laterally with respect to the machine. 90
- 90 In the form shown in Fig. 7, an extra insert web roll 22* is shown as mounted on the cover web roll shaft in such a position that it will be interposed between the second and third collected groups of sheets cut and fed from the main press web. 95
- 100 In Fig. 8, an extra insert web roll 22** is so mounted on the shaft of the insert web roll 22 that it will be interposed between the third and fourth collected groups of sheets cut and fed from the main press web. 105
- 110 Proceeding to describe the operation of 110

the machine in the form shown in Figs. 1 to 6 inclusive in which a completed signature is formed having one cover and one insert sheet combined with four groups of 5 collected sheets from the main press, as in the manner illustrated in Fig. 9, the cutters 24, 25, cut successive sheets from the insert web and feed them between the guides 26, 27, into position to have the advance edge of 10 an insert sheet engaged by the grippers 12. One insert sheet is transferred to the grippers 5 on the male folding cylinder 3 as the grippers 5 and 12 are brought together. In the meantime the cutters 33, 34, cut successive sheets from the cover web and feed the 15 sheets between the guides 35, 36, into position to have the advance edge of each sheet engaged by the grippers 14 on the transfer cylinder 13. One cover sheet is transferred 20 to the grippers 7 of the female folding cylinder 4 every revolution thereof when the grippers 7 and 14 are brought together. The rotary cutters 17, 18, which are driven at twice the speed of the cutters for the 25 insert and cover sheets, sever sheets from the web fed from the main press and feed them down between the guides 19 and 20. The collecting cylinder 9 is arranged to have its grippers 10 collect two sheets thereon 30 and then transfer the two sheets to the grippers 5 on the male folding cylinder 3 when the said grippers come together. As the grippers 5 and 7 on the two folding cylinders come together, the cover sheet on the 35 female folding cylinder will be transferred to the male cylinder, the grippers 5 on the male cylinder then engaging the advance edge of one insert sheet, two sheets from the main press and one cover sheet. As the 40 folding mechanism of the two cylinders 3 and 4 is brought into coaction, the grippers 5 are opened to release the advance edges of the collected group of sheets. The assembled cover, main press and insert sheets are 45 brought down between the tapes 67, 68 and the jaws 8 of the folding mechanism are opened to permit the tapes 67, 68 to feed the collected sheets between the slitters 69, 70, from whence the completed collection of 50 sheets drops into the pockets on the carrier 71. After the fourth successive movement of the pocket carrier 71, a completed signature will be delivered each step of the carrier with the sheets so combined that there 55 will be a cover sheet, two main press sheets, an insert sheet and three collected groups of two main press sheets in each completed signature.

It can be readily understood that instead 60 of transferring the advance edge of the cover sheet from the folding cylinder 4 to the folding cylinder 3 to be combined with the insert and main web sheets thereon, the opening of the grippers may be so timed 65 that the cover sheet will not be transferred

to the cylinder 3 but will be fed between the folding cylinders and have its advance edge released from the grippers 7 in ample time to permit the assembled insert, main web and cover sheets to be folded together and 70 fed between the tapes 67, 68.

It will be seen that the machine as hereinabove set forth accomplishes the assembling and folding together of sheets from the main press and from the insert and cover 75 supplies without the necessity of employing formers, turning-bars or carrying tapes. It is evident that various combinations of insert sheets within the collected groups of main press sheets in the completed signature may be accomplished by varying the 80 number of insert web supply rolls and varying the positions of the rolls on both the insert web roll shaft and on the cover web roll shaft. It will also be seen from the 85 above description that one or more insert sheets cut and fed from a previously printed source of insert supply may be combined with the sheets cut and fed from the main press web, and the sheets cut and fed from 90 the source of sheet supply in such manner that the insert sheet or sheets may be located at any desired point or points within the completed signature, this result being accomplished by the ability to feed the 95 insert sheets to different points in the width of the main web sheets and from both ends of the machine so that the insert sheets may occupy positions upon either side of the several collected groups of main press sheets 100 which go to form the complete signature.

What I claim is:

1. Folding cylinders, means for feeding main press sheets thereto, means for feeding an extra sheet from a single source of 105 extra sheet supply to the folding cylinders into engagement with said main press sheets at any one of a plurality of different points in the width of the main press sheets whereby the said extra sheet may occupy any one 110 of a plurality of positions between different plies in the completed signature, and means for combining the said main press sheets and extra sheet.

2. Folding cylinders, means for feeding 115 main press sheets thereto, means for feeding an extra sheet from a single source of extra sheet supply to the folding cylinders into engagement with said main press sheets, the source of extra sheet supply being shiftable 120 laterally whereby the said sheet may occupy any one of a plurality of positions between different plies in the completed signature, and means for combining said main press sheets and extra sheet.

3. Folding cylinders, means for feeding 125 main press sheets thereto, means for feeding an extra sheet from a single source of extra sheet supply to the folding cylinders into engagement with said main press sheets at 130

any one of a plurality of different points in the width of the main press sheets whereby the said extra sheet may occupy any one of a plurality of positions between different plies in the completed signature, and coacting folding devices arranged to fold the main press sheets and extra sheet together and deliver them at a predetermined point.

4. Folding cylinders, means for feeding main press sheets thereto, means for feeding an extra sheet from a single source of extra sheet supply to the folding cylinders into engagement with said main press sheets, the source of extra sheet supply being shiftable laterally whereby the said extra sheet may occupy any one of a plurality of positions between different plies in the completed signature, and coacting folding devices arranged to fold the main press sheets and extra sheet together and deliver them at a predetermined point.

5. Folding cylinders, means for feeding main press sheets thereto, means for feeding a sheet from a single source of extra sheet supply to the folding cylinders at different points in the width of the main press sheets according to the position which the extra sheet is to occupy between different plies in the completed signature, coacting folding devices arranged to fold the sheets together and deliver them at a predetermined point, means for slitting the so folded sheets into a plurality of groups and means for assembling the groups to form a completed signature.

6. Folding cylinders, means for feeding main press sheets thereto, means for feeding a sheet from a source of extra sheet supply to the folding cylinders, the source of extra sheet supply being shiftable laterally to permit the sheets fed therefrom to be fed to the folding cylinders at any one of a plurality of different points in the width of the main press sheets according to the position which the extra sheet is to occupy in the completed signature, coacting folding devices arranged to fold the sheets together and deliver them at a predetermined point, means for slitting the so-folded sheets into a plurality of groups, and means for assembling the groups to form a completed signature.

7. Folding cylinders, means for feeding main press sheets thereto and means for feeding extra sheets from a plurality of sources of extra sheet supply to the folding cylinders into engagement with the said main press sheets each at any one of a plurality of different points in the width of the main press sheets whereby each of the extra sheets may occupy any one of a plurality of positions between different plies in the completed signature and means for combining the said main press and extra sheets.

8. Folding cylinders, means for feeding

main press sheets thereto, means for feeding extra sheets from a plurality of sources of extra sheet supply to the folding cylinders into engagement with said main press sheets, the sources of extra sheet supply being shiftable laterally whereby each of the said extra sheets may occupy any one of a plurality of positions between different plies in the completed signature and means for combining said main press and extra sheets.

9. Folding cylinders, means for feeding main press sheets thereto, means for feeding extra sheets from a plurality of sources of extra sheet supply to the folding cylinders into engagement with the said main press sheets each at any one of a plurality of different points in the width of the main press sheets whereby each of the extra sheets may occupy any one of a plurality of positions between different plies in the completed signature and coacting folding devices arranged to fold the sheets together and deliver them at a predetermined point.

10. Folding cylinders, means for feeding main press sheets thereto, means for feeding extra sheets from a plurality of sources of extra sheet supply to the folding cylinders into engagement with said main press sheets, the sources of extra sheet supply being shiftable laterally whereby each of said extra sheets may occupy any one of a plurality of positions between different plies in the completed signature and coacting folding devices arranged to fold the sheets together and deliver them at a predetermined point.

11. Folding cylinders, means for feeding main press sheets thereto, means for feeding sheets from a plurality of sources of extra sheet supply to the folding cylinders at different points in the width of the main press sheets according to the positions which the extra sheets are to occupy in the completed signature, coacting folding devices arranged to fold the sheets together and deliver them at a predetermined point, means for slitting the so folded sheets into a plurality of groups and means for assembling the groups to form a completed signature.

12. Folding cylinders, means for feeding main press sheets thereto, means for feeding sheets from a plurality of sources of extra sheet supply to the folding cylinders, the sources of extra sheet supply being shiftable laterally to permit the sheets from each source to be fed to the folding cylinders at any one of a plurality of different points in the width of the main press sheets according to the positions which the extra sheets are to occupy in the completed signature, co-acting folding devices arranged to fold the sheets together and deliver them at a predetermined point, means for slitting the so-called sheets into a plurality of

groups and means for assembling the groups to form a completed signature.

13. Folding cylinders, means for feeding main press sheets thereto, means for feeding a cover sheet from one source of supply to the folding cylinders and means for feeding an insert sheet from another source of supply to the folding cylinders into engagement with the main press sheets at any one of a plurality of different points in the width of the main press sheets whereby said insert sheet may occupy any one of a plurality of different positions between different plies in the completed signature and means for combining said main press, cover and insert sheets.

14. Folding cylinders, means for feeding main press sheets thereto, means for feeding a cover sheet from one source of supply to the folding cylinders and means for feeding an insert sheet from another source of supply to the folding cylinders into engagement with the main press sheets, the source of insert sheet supply being shiftable laterally whereby said insert sheet may occupy any one of a plurality of different positions between different plies in the completed signature and means for combining said main press, cover and insert sheets.

15. Folding cylinders, means for feeding main press sheets thereto, means for feeding a cover sheet from one source of supply to the folding cylinders, means for feeding an insert sheet from another source of supply to the folding cylinders into engagement with the main press sheets at any one of a plurality of different points in the width of the main press sheets whereby said insert sheet may occupy any one of a plurality of positions between different plies in the completed signature and means for combining said main press, cover and insert sheets.

16. Folding cylinders, means for feeding main press sheets thereto, means for feeding a cover sheet from one source of supply to the folding cylinders, means for feeding an insert sheet from another source of supply to the folding cylinders into engagement with said main press sheets, the source of insert sheet supply being shiftable laterally whereby the insert sheet may occupy any one of a plurality of different positions between different plies in the completed signature, and coacting folding devices arranged to fold the sheets together and deliver them at a predetermined point.

17. Folding cylinders, means for feeding main press sheets thereto, means for feeding a cover sheet from one source of supply to the folding cylinders, means for feeding an insert sheet from another source of supply to the folding cylinders at different points in the width of the main press sheets according to the position which the insert

sheet is to occupy in the completed signature, coacting folding devices arranged to fold the sheets together and deliver them at a predetermined point, means for slitting the so folded sheets into a plurality of groups and means for assembling the groups to form a completed signature.

18. Folding cylinders, means for feeding main press sheets thereto, means for feeding a cover sheet from one source of supply to the folding cylinders, means for feeding an insert sheet from another source of supply to the folding cylinders, the source of insert supply being shiftable laterally to permit the feeding of sheets therefrom to the folding cylinders at any one of a plurality of different points in the width of the main press sheets according to the position which the insert sheet is to occupy in the completed signature, coacting folding devices arranged to fold the sheets together and deliver them at a predetermined point, means for slitting the so-folded sheets into a plurality of groups and means for assembling the groups to form a completed signature.

19. Folding cylinders, means for feeding main press sheets thereto, means for feeding a cover sheet from one source of supply to the folding cylinders and means for feeding a plurality of insert sheets from separate sources of supply to the folding cylinders into engagement with the main press sheets each at any one of a plurality of different points in the width of the main press sheets whereby each insert sheet may occupy any one of a plurality of positions between different plies in the completed signature and means for combining the main press, cover and insert sheets.

20. Folding cylinders, means for feeding main press sheets thereto, means for feeding a cover sheet from one source of supply to the folding cylinders and means for feeding a plurality of insert sheets from separate sources of supply to the folding cylinders into engagement with the main press sheets, the sources of insert sheet supply being shiftable laterally whereby each of said insert sheets may occupy any one of a plurality of different positions between different plies in the completed signature and means for combining the main press, cover and insert sheets.

21. Folding cylinders, means for feeding main press sheets thereto, means for feeding a cover sheet from one source of supply to the folding cylinders, means for feeding a plurality of insert sheets from separate sources of supply to the folding cylinders into engagement with the main press sheets each at any one of a plurality of different points in the width of the main press sheets whereby each insert sheet may occupy any one of a plurality of positions between different plies in the completed signature and

coacting folding devices arranged to fold the sheets together and deliver them at a predetermined point.

22. Folding cylinders, means for feeding 5 main press sheets thereto, means for feeding a cover sheet from one source of supply to the folding cylinders and means for feeding a plurality of insert sheets from separate sources of supply to the folding cylinders 10 into engagement with the said main press sheets, the sources of insert sheet supply being shiftable laterally whereby said insert sheet may occupy any one of a plurality of different positions between different plies in the completed signature, and coacting folding devices arranged to fold the sheets together and deliver them at a predetermined point.

23. Folding cylinders, means for feeding 20 main press sheets thereto, means for feeding a cover sheet from one source of supply to the folding cylinders, means for feeding a plurality of insert sheets from separate sources of supply to the folding cylinders 25 at different points in the width of the main press sheets according to the positions which the insert sheets are to occupy in the completed signature, coacting folding devices arranged to fold the sheets together and 30 deliver them at a predetermined point, means for slitting the so folded sheets into a plurality of groups and means for assembling the groups to form a completed signature.

35 24. Folding cylinders, means for assembling thereon sheets cut and fed from the main press web with a plurality of insert sheets fed from separate sources of sheet supply, coacting folding devices arranged 40 to fold the sheets together and deliver them at a predetermined point, means for slitting the so folded sheets into a plurality of groups and means for assembling the groups to form a completed signature.

45 25. Folding cylinders, means for assembling thereon sheets cut and fed from the main press web with a cover sheet fed from one source of sheet supply and a plurality of insert sheets fed from separate sources of 50 sheet supply, coacting folding devices arranged to fold the sheets together and deliver them at a predetermined point, means for slitting the so folded sheets into a plurality of groups and means for assembling the groups to form a completed signature.

55 26. Folding cylinders, a cylinder for transferring insert sheets one at a time to a predetermined point on one of the folding cylinders according to the position which

60 the insert sheet is to occupy in the completed signature, a cylinder for delivering a plurality of main press sheets to said folding cylinder, a cylinder arranged to transfer cover sheets one at a time to the other folding cylinder and means for folding the

65

sheets together and delivering them at a predetermined point.

27. Folding cylinders, a cylinder for transferring insert sheets one at a time to a predetermined point on one of the folding cylinders according to the position which the insert sheet is to occupy in the completed signature, a cylinder for delivering a plurality of main press sheets to said folding cylinder, a cylinder arranged to transfer 70 cover sheets one at a time to the other folding cylinder, means for folding the sheets together and delivering them at a predetermined point, means for slitting the so folded sheets into a plurality of groups and means for assembling the groups together to form a completed signature.

28. Folding cylinders, a cylinder for transferring insert sheets one at a time from a plurality of sources of insert sheet supply to a predetermined point on one of the folding cylinders according to the positions which the insert sheets are to occupy in the completed signature, a cylinder for delivering a plurality of main web sheets to said folding cylinder, a cylinder arranged to transfer cover sheets one at a time to the other folding cylinder and means for folding the sheets together and delivering them 80 at a predetermined point.

29. Folding cylinders, a cylinder for transferring insert sheets one at a time from a plurality of sources of insert sheet supply to a predetermined point on one of the folding cylinders according to the positions 90 which the insert sheets are to occupy in the completed signature, a cylinder for delivering a plurality of main web sheets to said folding cylinder, a cylinder arranged to transfer cover sheets one at a time to the other folding cylinder, means for folding the sheets together and delivering them 95 at a predetermined point, means for slitting the so folded sheets into a plurality of groups and means for assembling the groups together to form a completed signature.

30. Folding cylinders, a cylinder for transferring insert sheets one at a time to a predetermined point on one of the folding cylinders according to the position which the insert sheet is to occupy in the completed signature, a cylinder for delivering a plurality of main web sheets to said folding cylinder, a cylinder arranged to transfer cover sheets one at a time and also insert 115 sheets one at a time to the other folding cylinder and means for folding the sheets together and delivering them at a predetermined point.

31. Folding cylinders, a cylinder for 125 transferring insert sheets one at a time to a predetermined point on one of the folding cylinders according to the position which the insert sheet is to occupy in the completed signature, a cylinder for delivering 130

- a plurality of main web sheets to said folding cylinder, a cylinder arranged to transfer cover sheets one at a time and also insert sheets one at a time to the other folding cylinder, means for folding the sheets together and delivering them at a predetermined point, means for slitting the so folded sheets into a plurality of groups and means for assembling the groups together to form a completed signature.
32. Folding cylinders, a cylinder for transferring a plurality of insert sheets one at a time from separate sources of supply to a predetermined point on one of the folding cylinders according to the positions which the insert sheets are to occupy in the completed signature, a cylinder for delivering a plurality of main press sheets to said folding cylinder, a cylinder arranged to transfer cover sheets one at a time and also insert sheets one at a time to the other folding cylinder and means for folding the sheets together and delivering them at a predetermined point.
33. Folding cylinders, a cylinder for

transferring a plurality of insert sheets one at a time from separate sources of supply to a predetermined point on one of the folding cylinders according to the positions which the insert sheets are to occupy in the completed signature, a cylinder for delivering a plurality of main press sheets to said folding cylinder, a cylinder arranged to transfer cover sheets one at a time and also insert sheets one at a time to the other folding cylinder, means for folding the sheets together and delivering them at a predetermined point, means for slitting the so folded sheets into a plurality of groups and means for assembling the groups together to form a completed signature.

In testimony, that I claim the foregoing as my invention, I have signed my name in presence of two witnesses, this 9th day of July 1907.

EDGAR H. COTTRELL.

Witnesses:

F. GEORGE BARRY,
HENRY THIEME.
